FISHING LURE

Wilbur A. Huntley, Minneapolis, Minn., assignor to National Expert Bait Company, Inc., Minneapolis, Minn., a corporation of Minnesota

Filed Oct. 21, 1960, Ser. No. 62,572

Term of patent 14 years

(Cl. D31—4)

FIG. 1 is a view in front elevation of a fishing lure, showing my new design, the rear being substantially the same;

FIG. 2 is a view in top plan thereof;

FIG. 3 is a view in side elevation of one side thereof, the opposite side being substantially the same; and

FIG. 4 is a view in bottom plan thereof.

The portions shown by dotted lines in FIG. 1 are for illustrative purposes only.

I claim:

The ornamental design for a fishing lure, as shown and described.
